UNITED STATES PATENT OFFICE.

HARRY WALCOFF, OF NEW YORK, N. Y.

KNICKERBOCKERS.

Patented July 2, 1918.

1,271,248.

Specification of Letters Patent.

Application filed February 11, 1918. Serial No. 77,564.

To all whom it may concern:

Be it known that I, HARRY WALCOFF, a citizen of the United States, and resident of New York, county and State of New York, have invented certain new and useful Improvements in Knickerbockers, of which the following is a specification.

My invention relates to knickerbockers and more particularly to such as are usually worn by children and youths. Such knickerbockers are usually unlined and being oftentimes made of material having a rough inner surface exert an injurious frictional action on the underwear or uncomfortably 10 contact with the person of the wearer. In addition such knickerbockers are often internally soiled and to clean same must then be washed as a unit, an operation which is oftentimes injurious to the fabric and cut of 15 the knickerbocker, particularly in the case of cheap garments. My improvement has for its object to overcome the above objectionable features by providing such garments with a removable lining which by 20 being interposed between the fabric of the knickerbocker and the underwear or person of the wearer prevents injurious or uncomfortable contact therewith and by being easily detached from the garment may be 25 easily washed or cleaned as a separate unit. My improvement will be fully described 30 hereinafter and the features of novelty will be pointed out in the appended claim.

An example of my invention is shown in 35 the accompanying drawings in which Figure 1 is an outside view of a pair of knickerbockers with my improvement incorporated therein; Fig. 2 is a sectional view on the line 2-2 of Fig. 1 and Fig. 3 is a horizontal section on the line 3-3 of Fig. 1.

As illustrated in the drawings the knickerbockers comprise the usual body 5 and integral leg sections 6, the body in the illustrated example being formed with opposed 45 edges 7 and 8 adapted to be detachably secured together in any suitable manner as by means of button-holes 9 and buttons 10 to open and close the usual front opening of garments of this type. The latter may also 50 be provided with an inner waist-band 11 and may further include any other features or elements which are customarily present in garments of the kind in question.

My improved lining comprises a body 12 55 preferably having a waist band 13 and formed integrally or otherwise with leg sec-

tions 14 and further constructed with opposed edges 15 and 16 arranged to be detachably secured together for instance by means of a button 17 and button-hole 18 and forming a front opening in said lining. The body 12 and leg sections 14 are so dimensioned, cut and constructed as to fit smoothly and nicely within the corresponding portions of the knickerbocker, and in substantial surface contact therewith, with the edges 15 and 16 adjacent to the edges 7 and 8 so as to bring the front opening of the lining into proper and exact registry with the front opening of the knickerbocker. In order that said lining may be secured in operative combination with said knickerbockers and yet be easily removed therefrom when desired I prefer to provide the waist band 13 with one or more button-holes 19 adapted to coöperate with buttons 20 located either directly on the inner surface of the waist band 11 of the garment or carried by tabs 11^a which depend from said waist-band 11 at suitable intervals as shown. The lining may be constructed of any material which is usually used for such purposes and when combined with the garment provides a protecting layer located between the knickerbocker and the underwear or person of the wearer. The said lining thus receives all the frictional rubbing of the knickerbocker and prevents the same from exerting a wearing action on the underwear and at the same time may serve to maintain said knickerbocker out of uncomfortable contact with the person of the wearer. The said lining also protects the knickerbocker against interior soiling and if it becomes soiled itself may be readily removed from the garment and separately washed or otherwise cleaned. By fitting the lining to the interior of the knickerbocker a perfectly smooth result is obtained and objectionable creasing and folding is prevented or reduced to a minimum while uncomfortable seams or the like are also avoided. The lining further serves to cover any rough seams which may be included in the garment.

It will be seen that my improved lining 105 fully protects the knickerbocker throughout not only against interior soiling but also against the necessity of being more or less continuously subjected to a washing or cleaning process. This is a decided advantage as garments of the type under discussion, particularly cheap garments are often

constructed of materials which shrink or otherwise lose their intended shape if subjected to too frequent washings. My improvement is easy to manufacture and does

5 not add materially to the cost of the garment and may readily be incorporated in or combined with the knickerbocker.

When the tabs 11^a are included in the arrangement the lining is secured in the garment without interference with the means whereby such knickerbockers are generally attached to other garments or the like for supporting purposes. If the knickerbocker is provided with side or other openings instead of the front opening shown and described the lining is accordingly constructed as will be readily apparent.

Various changes in the specific form shown and described may be made within

the scope of the claim without departing 20 from the spirit of my invention.

I claim:

The combination of a pair of knickerbockers comprising a body and leg sections, an interior waist-band combined with said knickerbockers, a series of tabs depending from said waist-band at intervals, fastening devices carried by said tabs, a lining comprising a body and leg sections fitted within the corresponding portions of the knickerbockers and fastening means on said lining adapted to coöperate with the fastening devices on said tabs to removably secure said lining in said knickerbockers. 30

In testimony whereof I have hereunto set 35 my hand.

HARRY WALCOFF.
